UNITED STATES PATENT OFFICE.

OLIVER THORN, OF LONDON, ENGLAND.

DESIGN FOR A SPADE-CARRYING ATTACHMENT FOR CYCLES.

SPECIFICATION forming part of Design No. 33,385, dated October 16, 1900.

Application filed August 11, 1900. Serial No. 26,657. Term of patent 7 years.

To all whom it may concern:

Be it known that I, OLIVER THORN, a subject of the Queen of Great Britain and Ireland, residing at London, England, (and whose post-office address is No. 19 Great Portland street, Oxford street, London, England,) have invented and produced a new and original Design for a Spade-Carrying Attachment for Cycles, of which the following is a specification.

My invention relates to a new and original design for a spade-carrying attachment for cycles; and the design consists of the essential characteristics herein referred to and shown in the accompanying drawings.

In the accompanying drawings, which illustrate my design, Figure 1 is an elevation. Fig. 2 is also an elevation, taken at right angles to the view shown in Fig. 1 and looking to the left in said figure; and Fig. 3 is an end view looking down in Fig. 1.

d designates an elongated flattened and continuous loop having a gradual curvature

throughout its length, and *aa* designate a pair of spaced members, the counterpart of each other, extending from opposite edges of the loop *d* at its concave side. The members *aa* each have a curved portion in the form of an arc of a circle in the region of their connection with the loop *d* and a straight portion at its free end.

The essential features of the design are the elongated curved shape of the loop *d* and the relative positions of the members *aa* with respect to each other and to the loop portion *d*.

What I claim is—

The design for a spade-carrying attachment for cycles, as herein shown and described.

In witness whereof I have hereunto set my hand in the presence of two witnesses.

OLIVER THORN.
